CHAIR OR SIMILAR ARTICLE

Donald Lee Sickler, Baltimore, Md., assignor to National Industries, Inc., Odenton, Md., a corporation of Maryland

Filed Nov. 6, 1967, Ser. No. 9,293

Term of patent 14 years

Int. Cl. D6—01

U.S. Cl. D15—1

FIG. 1 is a view in perspective of the chair with the chair pedestal shown in dotted lines, the chair seat and back frame shown in solid lines and the upholstery for the chair seat and back shown in dotted lines;

FIG. 2 is a side elevational view of the chair seat with the base omitted for convenience of illustration;

FIG. 3 is a rear perspective view of the chair seat illustrated in FIG. 2;

FIG. 4 is a plan view of the seat and back frame with the seat and backrest cushions illustrated in dotted line; and

FIG. 5 is a bottom view of the seat and back frame with the seat and backrest cushions illustrated in dotted line.

The dominant features of my design are recited in those portions shown in full lines on the drawings.

I claim:

The ornamental design for a chair or similar article, as shown and described.
